ARCH SUPPORTING SHOE

Doris Franklin Walker, Gastonia, N. C.

Application September 11, 1937, Serial No. 163,402

1 Claim. (Cl. 36—8.5)

This invention relates to an arch-supporting shoe and a method of making the same.

One of the objects of the invention is to provide a novel arch-supporting shoe which will give a more adequate support to the arch of the foot, and I accomplish this by using a relatively wide, properly shaped arch-supporting shank member which underlies the insole of the shoe and which is of a width and shape to extend at least to the inner edge of the insole along the shank portion thereof, and in order to make a proper connection between the upper and the insole on the inside of the shoe at the shank portion I propose to provide the upper with an extension on its inner side which extends across and underlies the shank member and is secured to the insole along the outer edge thereof.

In making my improved shoe the insole and shank member are assembled as usual and then the edge of the upper is attached to the insole from a point on the inner edge thereof immediately back of the ball of the foot and immediately in front of the shank member, around the toe portion and along the outer edge of the outsole by any suitable or usual means. The extension on the inner edge of the upper is then drawn across the shank portion of the shoe and secured to the insole along or adjacent the outer edge thereof at the shank portion. The outer sole may then subsequently be attached to the shoe bottom, preferably by the cementing operation.

In order to give an understanding of the invention I have illustrated in the drawings some selected embodiments thereof which will now be described after which the novel features will be pointed out in the appended claim.

In the drawings:

Fig. 1 is a bottom view of an insole adapted for use in making a shoe embodying my improvements, the dotted lines in Fig. 1 indicating the shape and location of the arch-supporting shank member;

Fig. 2 is a view of the arch-supporting shank member before the extension is given its curved shape;

Fig. 3 is an enlarged section on the line 3—3, Fig. 5;

Fig. 4 is a view similar to Fig. 3 but showing the edge of the upper extension sewed to the inseam-receiving rib of the outsole;

Fig. 5 is a bottom plan view of a shoe embodying my invention, said figure illustrating the shoe after the upper has been attached to the insole but before the outsole has been applied;

Fig. 6 is a fragmentary view showing the bottom of an insole with a different form of arch-supporting shank member applied thereto;

Fig. 7 is a perspective view of the arch-supporting shank member illustrated in Figs. 1, 2, 3 and 4;

Fig. 8 is a diagrammatic perspective view of the shoe upper showing the extension thereon which is carried across the shank member;

Fig. 9 is a view of a pad member which may be inserted between the insole and the shank member in order to increase the arch-supporting quality of the shoe;

Fig. 10 is a section on the line 10—10, Fig. 9.

I have herein illustrated my invention as it might be embodied in making a welt shoe in which the outer sole is cemented to the shoe bottom. In the drawings, 1 indicates the insole of the shoe, 2 is the upper, 3 the lining for the upper. If the invention is embodied in a welt shoe I propose to provide the insole with an inseam-receiving rib 4 to which the edge 17 of the upper and the welt 5 is sewed as indicated at 6 in Figs. 3 and 4.

In order to provide an adequate support for the arch of the foot I propose to employ an arch-supporting shank member of somewhat resilient metal, which shank member is of a width and shape to extend at least to the inner edge of the insole along the shank portion thereof. In Figs. 1 to 4 this arch-supporting shank member is indicated at 7 and it is secured to the insole in the usual way by means of tacks that are driven through holes 8 formed in the heel end thereof for that purpose. The shank member 7 is formed on its inner edge with an upwardly curved extension 9 which curves around and partially embraces the inner side of the shank portion of the foot, and where this form of shank member is employed I will preferably make the insole with an extension 10 projecting from its inner edge at 40 the shank portion thereof, said extension 10 of the insole having a shape corresponding to the extension 9 of the shank member.

In making a welt shoe the insole will be so made that the inseam-receiving rib 4 will terminate on the inner edge portion of the insole at a point immediately back of the ball of the foot and immediately in front of the shank member 7 as indicated at 11 in Fig. 1. The toe portion 12 of the upper is formed with an extension 13 on 50 the inner edge, said extension 13 being of a length to extend across the bottom of the insole.

In the making of the shoe the latter is lasted in the usual way except that during this operation the extension 13 of the upper is drawn across 55

the shank portion of the insole and secured thereto at the outer edge thereof in some suitable way as by means of tacks 14.

If the shoe is a welt shoe then the welt 5 and the edge 17 of the upper will be sewed to the inseam-receiving rib by the stitches 6, this operation being similar to that employed in making welt shoes except that on the inner side of the insole the welt will terminate at the end 11 of the inseam-receiving rib, as shown at 15 in Fig. 5. If desired, the extension 13 of the upper which underlies the shank portion of the insole may be of sufficient length so that the edge 18 thereof will lie against the outer face of the inseam-receiving rib 4, in which case said edge 18 of the extension 13 will be sewed to the inner side of the inseam-receiving rib during the operation of stitching the welt and upper to the outer side of said rib. This will produce a shoe constructed as shown in Fig. 4.

After the welt has been thus secured to the shoe then the outsole 19, indicated in dotted lines in Figs. 3 and 4, may be cemented to the shoe bottom in any approved way.

25 By making the arch-supporting shank member 1 with the extra width at the shank portion and giving it the shape shown in Figs. 1-4 said shank provides an improved and adequate support for the arch at the shank of the foot. Although the presence of the metal shank member which has its edge extending to the inner edge of the insole along the shank portion prevents the upper from being attached directly to the inner edge of the insole at this point, yet by 35 making the upper with the extension 13 which extends across the shank of the insole and which is secured to the insole at the outer edge thereof, a shoe is provided in which the upper and insole are properly held together at the shank portion. 40 Instead of having the shank member formed with the upwardly curved extension 9 as shown in Figs. 1-4 and in Fig. 7, I may employ a shank member 1a constructed as shown in Fig. 6 and which is formed so that the inner edge 22 thereof 45 comes substantially flush with the inner edge 21 of the insole at the shank portion. This form of arch-supporting shank member will have sufficient arch-supporting qualities for many types of shoes. 50 The arch-supporting shank member 1a is shaped so that its inner edge 22 which is substantially flush with the inner edge 21 of the insole is of considerable length and extends approximately to the heel portion. 55 It will be noted that in all forms of the invention the arch-supporting shank member extends at least to the inner edge of the insole at the shank portion of the shoe and thus provides a more adequate support for the arch. It will also 60 be noted that in order to secure a proper connec-

tion between the upper and the insole at the shank of the foot said upper is provided with the extension 13 which extends across the insole and underlies the shank member and is secured to the insole along the outer edge portion thereof either by tacks 14, as shown in Figs. 3 and 5, or by having its edge 18 stitched to the inseam as shown in Fig. 4.

The arch-supporting shank member 1 or 1a may be placed directly on the bottom face of the insole as shown in Figs. 4 and 6, in which case both the lining and the outer ply of the extension 13 of the shoe upper would lie across the shank member, or said shank member might be inserted between the lining portion of the extension 13 and the outer ply portion as shown in Fig. 4.

While I have shown the invention as applied to a welt shoe, yet it is equally applicable to shoes of other types, and hence I do not wish to be limited to the use of the invention in connection with a welt shoe.

An advantage of my improvement is that if it is found that the arch-supporting shank member does not give sufficient support to the arch it is possible for the person wearing the shoe to remove the edge portion 10 of the insole from the arch-supporting member and insert a pad 20 of felt or similar material beneath the edge of the insole. This will have the effect of raising the edge of the insole at the shank of the foot and thus providing additional support for the arch.

I claim:

A shoe having an insole provided with an inseam-receiving rib having one end terminating at a point on the inner edge of the insole immediately back of the ball and extending from said point around the toe portion and along the outer edge of the shank, a metal arch-supporting shank member beneath the sole having its inner edge extending substantially to the inner edge of the insole at the shank portion and being of a width to extend from said inner edge across and beyond the median line of the insole, a welt co-extensive in length with said inseam-receiving rib, an upper having its edge secured to the inseam-receiving rib and to the welt throughout the entire extent of said rib, said upper having on its inner face an extension which extends across the insole and shank member and the edge of which is secured to the insole along the outer marginal portion thereof, and an outsole cemented to the exposed portion of the insole, the welt and said extension of the upper, said shoe being weltless on the inner side of the shank portion thereof for the full width of said upper extension and the insole being free from the upper along the weltless portion of the inside of the shoe.

DORIS FRANKLIN WALKER. 60
